UNITED STATES PATENT OFFICE

WILLIAM BADEN, OF CHICAGO, ILLINOIS

WATER HEATER

Application filed March 16, 1928. Serial No. 262,119.

This invention relates in general to heaters and more particularly to water heaters which are so contructed and assembled that the water is heated at a minimum expense.

One object of this invention is the production of a heater which receives its heating medium, either water or steam, from an adjacent boiler, whereby it will be heated without the necessity of employing additional heating means other than the adjacent boiler.

Another object of this invention is the production of a heater, including a number of heating tubes communicating with recessed caps to permit of an uninterrupted circulation of the water to be used as it is heated.

A still further object of this invention is the production of a heater in which the several parts are readily accessible and removable, thereby permitting the heater to be thoroughly cleaned of sediment or lime deposits whenever desired or allowing faulty parts to be easily removed and perfect parts to be substituted.

With the foregoing and other objects in view, attention is directed to the accompanying drawings, wherein like reference numerals indicate like parts in the several figures, wherein

Fig. 1 is a diagrammatic view of a water heating system, showing the water heater in operation in conjunction with a boiler and a storage tank;

Fig. 2 is a vertical sectional view through the water heater, taken on the line 2—2 of Fig. 1, looking in the direction of the arrows;

Fig. 3 is a vertical sectional view of the water heater, taken on the line 3—3 of Fig. 1, looking in the direction of the arrows;

Fig. 4 is another vertical sectional view of the water heater, taken on the line 4—4 of Fig. 1, looking in the direction of the arrows;

Fig. 5 is still another vertical sectional view of the water heater, taken on the line 5—5 of Fig. 1, looking in the direction of the arrows;

Fig. 6 is a longitudinal sectional view through the assembled water heater looking in the direction of the arrows on line 6—6 of Fig. 2;

Fig. 7 is a longitudinal sectional view

through the water heater in the direction of the arrows shown on line 7—7 of Fig. 2 and the opposite direction to Fig. 6;

Fig. 8 is a vertical sectional view through the central portion of the water heater, taken on the line 8—8 of Fig. 7;

Fig. 9 is a fragmentary sectional view, showing the manner in which one of the heating tubes is mounted in an end supporting plate;

Fig. 10 is a fragmentary sectional view, taken on the line 10—10 of Figure 9, looking in the direction of the arrows;

Fig. 11 is a sectional view taken on the line 11—11 of Fig. 10; and

Fig. 12 is an elevation of the water heater, showing the manner in which a number of the casings may be connected together to provide for the heating of large quantities of water.

Referring more specifically to the drawings, the water heater is indicated by 1, a water or steam boiler is shown at 3 and a hot water storage tank 2 is likewise illustrated in Fig. 1. The cold water of a city supply passes into the tank 2 through the pipe 4 and then passes from the tank 2 through the pipe 5 to the water heater 1. The movement of the cold water through the pipe is controlled by the valve 6, while the cock 7 is also connected to the pipe 5, for purposes yet to appear. A return pipe 8 is also provided to connect the water heater to the storage tank 2 and it is through this pipe that the heated water passes from the water heater to the tank 2. The hot water to be used is conducted from the tank 2 by the valved pipe 9. There is also provided a valved pipe 5' connected to pipe 5, as shown in Fig. 1. When desired the valve 6 may be closed and water circulated rapidly through tank 2 by pipes 4, 5, and 5' for cleaning sediment from the tank 2.

The water heater 1 obtains its heating medium, either hot water or steam, from the supply pipe 10, this supply pipe 10 being connected to the boiler 3. The movement of steam or hot water through the pipe 10 is controlled by the valve 11. After the hot water or steam from the boiler 3 passes

through the water heater 1, it is returned to the boiler 3, through the return pipe 12, which has a valve 13 and a cock 14, for purposes yet to appear.

5 The water heater 1 consists of a casing 15, which is elongated as illustrated clearly in Figs. 1, 6, and 7. This casing 15 may be substantially elliptical in cross section, as shown in Fig. 8, although it is obvious that it 10 may be round or square, without departing from the spirit of the present invention. Flanges 16 and 17 are formed integral with the casing 15 and extend outwardly therefrom. The end supporting plates 18 and 19 15 entirely close the ends of the casing 15 and are secured to the flanges 16 and 17 by the screws 20. Packing disks 21 are interposed between the flanges and end plates, thereby forming a water-tight closure, as illustrated 20 in Figs. 6 and 7.

The primary end cap consists of a back 22 and an integral inwardly extending collar 23, having formed thereon an outwardly extending flange 24. A central vertically 25 extending partition 25 is formed within the cap and extends from the top to the bottom thereof, as illustrated in Fig. 3. A horizontal partition 26 is likewise formed within the cap and extends from one side of the cap to the 30 central portion of the vertical partition 25. This primary end cap, consisting of a back, collar, flange, and partitions is formed as a unit, the outer edges of the partitions terminating evenly with the face of the flange 24. The arrangement of the partitions within the cap form an entrance recess 27 and exit recess 28 formed thereabove, while opposite these two recesses and on the other side of the vertical partition 25 is an enlarged 35 vertically-extending circulation recess 29.

The secondary cap is positioned upon the opposite end of the casing and consists of a back 30 and an integral inwardly extending collar 31, having formed thereon an outwardly extending flange 32. A central horizontally extending partition 33 is formed within the cap and extends from one side of the cap to the other and the outer edge of this partition terminates evenly with the face of the flange 32. The arrangement of this horizontally extending partition 33 forms an enlarged lower circulation recess 34 and an enlarged upper circulation recess 35.

When the water heater is in an assembled condition suitable packing or packing disks 36 is or are interposed between the supporting end plates 18 and 19 and the flanges 24 and 32 of the recessed end caps. These end caps are 40 held in demountable positions by bolts 37, which pass through the flanges of the casing and of the end caps, as well as the end plates, as illustrated in Fig. 1. By referring particularly to Fig. 6, it will be seen that the partitions, in conjunction with the support-

ing end plates 18 and 19, form water-tight recesses.

The heating tubes 38 extend longitudinally of the casing as shown in Fig. 6. The ends of these are carried by the end supporting plates 70 18 and 19 in a manner to be more fully explained. The heating tubes 38 communicate with the entrance recess 27 of the primary cap and at their opposite ends with the lower circulation recess 34, at one side thereof, of the secondary cap. The inclined heating tubes 39 communicate with and lead from the opposite side of the recess 34 and the discharge ends of the tubes 39 communicate with the lower portion of the vertically extending circulation recess 29. The heating tubes 40 communicate with and lead from the upper portion of the vertically extending circulation recess 29, as illustrated in Fig. 7, and communicate with and discharge into one side portion of the upper circulation recess 35. The heating tubes 41 communicate and lead from the opposite side portion of the recess 35 and communicate and discharge into the exit recess 28. While Figs. 2 and 4 are elevations of the end supporting plates 18 and 19 and illustrate the manner in which the ends of the heating tubes are mounted in the supporting plates, the dotted lines on these figures show the manner in which the end caps including the several partitions fit upon these supporting plates, and thereby form the interior recesses, hereinbefore referred to and the manner in which the heating tubes lead into or out of the recesses. By referring to Figs. 6 and 7 it will be seen that the heating tubes are inclined so that their discharge ends are higher than their intake ends, thus aiding in the circulation of the water as it is being heated.

These heating tubes are supported by the end supporting plates in the manner most clearly illustrated in Figs. 9, 10, and 11. The plates 18 and 19 are provided with a number of internally threaded pockets 42 having at their inner portions abutment collars 43. The heating tubes extend through the abutment collars and the ends of the tubes fit with externally threaded ferrules 44, these ferrules 44 being screwed into the pockets 42 and bearing upon the packing 45 in the pockets, thereby forming a water-tight connection. This construction in effect forms a stuffing box on the end of each tube, which permits the expansion or contraction, of the tubes due to heat or cold, and since each tube is provided with a pair of such stuffing boxes, it is obvious that the action just referred to is independent on each tube.

It is apparent from the drawings that the heating tubes are arranged in parallel and not in series, and for this reason the possible clogging of one tube will not in the least affect the flow of the water through the remaining tubes. Furthermore, the arrange-

ment of the tubes as just specified provides an enlarged heating area, thus permitting a larger quantity of water to be heated. It should also be understood, that in the event 5 one of the tubes becomes leaky or otherwise defective and it is impossible to immediately replace it with a new tube, the defective tube may nevertheless be removed and the corresponding pockets 42 closed by the insertion of 10 wooden plugs and in this event the water heater will efficiently and properly function on the remaining heating tubes. Attention is especially invited to the fact that the heating tubes of this invention are straight throughout 15 their entire lengths, thus eliminating friction producing curves or bends and allowing sediment or lime deposits to be removed from their interiors by drilling or ramming. One of the end caps may be readily removed 20 when the latter action is desired and then the sediment is pushed into the other end cap, from which it will be easily removed when the heater is flushed. The heating tubes are preferably formed of copper and have their 25 ends plain, thus permitting of their insertion or removal with very little trouble.

In operation the cold supply of water flows through the pipe 5 into the entrance recess 27 of the primary cap. The flow is continued 30 through the heating tubes 38 and the water is discharged from the upper end of these tubes 38 into the lower circulation recess 34. The water is then received from the recess 34 by the heating tubes 39 and is discharged from 35 the upper ends of these tubes 39 into the lower portion of the vertically extending circulation recess 29. The water then passes from the upper portion of the recess 29 through the heating tubes 40 and is discharged from 40 the upper ends of the tubes 40 into one side portion of the upper circulation recess 35. The water then passes from the remaining side portion of the recess 35 through the heating tubes 41, being discharged from the upper 45 ends of the tubes 41 into the exit recess 28, from whence it flows through the pipe 8 into the hot water storage tank 2. During this flow of the water to be used the casing 15 is filled with heated water or steam, which has 50 been received from the boiler 3 through the pipe 10 and returned to the boiler 3 by the pipe 12.

While this invention has been described as used for heating water, it may likewise be 55 used for pre-heating oil for oil burners.

The various parts used in the assembly of this water heater are of very simple construction so that its cost of construction is very reasonable. There is no expensive brazing or 60 welding involved and, furthermore, the elimination of either or both of these common practices has been found from experience to eliminate troublesome leaks resulting therefrom. Avoiding these practices, for example, 65 permits of the removal of the heating tubes

so that lime deposits or sediment thereon may be scraped therefrom. The tubes may then be replaced and a water-tight union is formed by the stuffing boxes above described, the packing being tightened when required.

70

By referring to Fig. 12 it will be seen that a number of casings 1 may be connected together, with the end caps on the outer ends of the two endmost casings. The casings 1 in this instance may be fed with heated water or steam from the pipe 10' and the heated water or steam being returned to the boiler by the return pipe 12'. The heating tubes, under this form of operation would be rather long to pass entirely through all 75 of the casings 1 to communicate with the end caps, the operation of the tubes being as above set forth. Thus it will be seen that the water heater is adaptable for any capacity as additional sections can be added to its length and longer heating tubes substituted 80 for the ones used when a single casing is used.

85

When it is desired to clean out the casing 15, the valve 13 in pipe 12 may be closed and the cock 14 opened and the sediment will then be discharged. Access may also be had to the interior of the casing by the removal of the plug 46, at which time the valves 11 and 13 may be closed and the cock 14 opened and 90 an auxiliary cleaning agent forced through the casing for cleaning purposes. Afterwards the plug must be replaced, as shown in Figs. 6, 7, and 8.

95

As most of the sediment gradually settles 100 to the bottom, the tubes and caps may be cleaned by merely opening the cock 7 and closing the valve 6 and the valve pipe 9, when the tubes and caps will drain and the sediment pass out at such time.

105

While the preferred construction and operation of the present invention has been disclosed and described, it is apparent that I do not wish to limit this invention to the specific details disclosed and described, but do desire to include all modifications and changes as come within the scope of the invention as claimed.

110

Having described the construction and operation of my invention, what I claim is 115 new and desire to cover by Letters Patent is:

A hot water heater comprising a casing, tubing sheet plates connected with the ends of the casing, head caps connected with the casing and housing the sheet plates, one of 120 said caps having a vertical partition engaging the adjacent sheet plate and a horizontal partition engaging said plate extending from one side of the cap to the vertical partition, said last mentioned sheet plate and the partitions defining a lower small cold water inlet and an upper small hot water outlet chamber and a large circulating chamber, a horizontal partition extending across the 125 other cap engaging its adjacent sheet plate 130

and defining in connection therewith upper and lower circulating chambers, tubes extending from one sheet plate to the other inclining from the cold water inlet chamber to the lower circulating chamber of the other cap, tubing extending from the last mentioned circulating chamber to the large circulating chamber of the first mentioned cap, tubes extending through the sheet plates connecting the large circulating chamber to the upper circulating chamber, and tubes extending through the sheet plates connecting the upper circulating chamber with the small upper outlet chamber.

15 In testimony whereof I affix my signature.
WILLIAM BADEN.
